UNITED STATES PATENT OFFICE

116,798

DESIGN FOR A COMBINED CULINARY MIXER AND BEATER, OR THE LIKE

Hulda M. Erickson, Isanti, Minn.

Application July 13, 1939, Serial No. 86,002

Term of patent 14 years

To all whom it may concern:

Be it known that I, Hulda M. Erickson, a citizen of the United States of America, residing at Isanti, in the county of Isanti, in the State of Minnesota, have invented a new, original, and ornamental Design for a Combined Culinary Mixer and Beater, or the like, of which the following is a specification, reference being had to the accompanying drawing, forming part thereof.

In the drawing:

The dominant feature of the design resides in the portion shown in full lines.

What I claim is:

The ornamental design for a combined culinary mixer and beater, or the like, substantially as shown and described.

HULDA M. ERICKSON.
